DESIGN FOR A KNIFE HANDLE

Ward McMillen, Toledo, Ohio

Application October 30, 1947, Serial No. 142,223

Term of patent 14 years

(Cl. D44—29)

To all whom it may concern:

Be it known that I, Ward McMillen, a citizen of the United States of America, residing at Toledo, in the county of Lucas and State of Ohio, have invented a new, original, and ornamental Design for Knife Handle, of which the following is a specification, reference being had to the accompanying drawings, forming part thereof.

Figure 1 is an isometric view of a knife handle, showing my new design;

Figure 2 is a top plan view;

Figure 3 is a side elevational view;

Figure 4 is a front end view;

Figure 5 is a sectional view taken on line 5—5 of Figure 3;

Figure 6 is a sectional view taken on line 6—6 of Figure 3; and

Figure 7 is a sectional view taken on line 7—7 of Figure 3.

I claim:

The ornamental design for a knife handle, substantially as shown.

WARD McMILLEN.
